Electric Assisted Bicycle, Tokusengai, p. 107, vol. 41, No. 10, Sep. 2019, Makino Shuppan Co., Ltd.

Primary Examiner — Darlington Ly

(57) **CLAIM**

The ornamental design for an electric bicycle, as shown and described.

DESCRIPTION

FIG. 1 is a front elevation view of an electric bicycle embodying our new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is a top, front and left side perspective view thereof. The broken lines in the drawings illustrate portions of the electric bicycle that form no part of the claimed design.
